UNITED STATES PATENT OFFICE

167,775

PAINT BRUSH

Andrew A. Schmidt, Los Angeles, Calif.

Application October 22, 1951, Serial No. 17,063

Term of patent 14 years

(Cl. D9—2)

To all whom it may concern:

Be it known that I, Andrew A. Schmidt, a citizen of the United States and a resident of Los Angeles, in the county of Los Angeles, and State of California, have invented a new, original, and ornamental Design for a Paint Brush, of which the following is a specification, reference being had to the accompanying drawing, forming a part thereof.

Figure 1 is an elevational view of a paint brush showing my new design;

Figure 2 is a side view thereof;

Figure 3 is a section taken along line 3—3 of Figure 1;

Figure 4 is a section taken along line 4—4 of Figure 1; and

Figure 5 is a section taken along line 5—5 of Figure 1.

The side of the brush not illustrated in the drawing is identical to the side shown in Figure 1.

I claim:

The ornamental design for a paint brush, substantially as shown and described.

ANDREW A. SCHMIDT.
